STRAIGHT BAR KNITTING MACHINE

Thomas Charles Bromley and Arthur Shortland,
Leicester, England, assignors to Mellor Bromley
and Co. Limited, Leicester, England

Application November 25, 1942, Serial No. 466,891
In Great Britain October 17, 1941

7 Claims. (Cl. 66—110)

This invention is for improvements in and relating to straight bar knitting machines wherein sinkers are moved in unison by means of a catch bar, and is primarily concerned with machines (of which the Cotton's patent is the chief embodiment) wherein sinkers are projected one after another by a slurcock or equivalent device but are also moved in unison by a catch bar. In a Cotton's patent machine, jack sinkers, which have short butts, are projected one after another by the slurcock and subsequently dividing sinkers, having long butts, are projected in unison between the jack sinkers by a catch bar which is always engaged with the butts of the dividing sinkers, while at a later stage all the sinkers are retracted in unison by the catch bar. To this end the catch bar has a rising and falling motion to engage with and disengage from the butts of the jack sinkers, and also a motion towards and away from the sinker head to move the sinkers. Prior to the projection of the jack sinkers the catch bar is in a rearward position and is also elevated so that its front lip is clear of the butts of the jack sinkers, thereby permitting the latter to be projected one by one by the traverse of the slurcock. After this projection the catch bar is advanced towards the sinker head to project all the dividing sinkers in the operation of dividing and also to hold the jack sinkers and the dividing sinkers against the verge plate or equivalent part of the sinker head. The catch bar is then lowered so that it engages the butts of the jack sinkers, and at a subsequent stage is retracted from the sinker head so that all the sinkers are retracted in unison. Still later it is raised so that its front lip is above the butts of the jack sinkers and everything is ready for the next slurcock traverse. Not only is the mechanism by which these movements are imparted to the catch bar complicated, but the rising and falling movement of the catch bar to disengage from and engage with the butts of the jack sinkers introduces difficulties. It sometimes occurs that owing to a slightly misplaced jack sinker or a burred edge on the butt thereof the catch bar fails to be lowered into correct engagement with the jack sinker butts and as a result, when the said bar is retracted, the jack sinkers are left in the forward position. The present invention seeks to overcome these disadvantages.

According to the present invention, in a Cotton's patent or other straight bar knitting machine there is a catch bar comprising two separately movable parts, a front part for engaging in front of sinker butts to retract them, and a rear part for engaging behind sinker butts to

5 advance them, together with means for moving said parts towards and away from the sinker head or bed. Thus rising and falling movements of the catch bar are rendered unnecessary. As will be 10 appreciated the invention is primarily concerned with a machine wherein jack sinkers or their equivalent are advanced one by one, dividing sinkers are advanced in unison, and all the sinkers are retracted in unison. The invention provides, 15 in such a machine, means arranged to effect the following movements: forward movement of the front part prior to the projection of the jack sinkers; forward movement of the rear part to advance the dividing sinkers subsequent to the projection of the jack sinkers; retraction of the 20 front part to retract all sinkers.

The foregoing and other features of the invention, set out in the appended claims, are incorporated in the construction that will now be described with reference to the accompanying drawings, in which

Figure 1 shows the relevant parts of a Cotton's patent machine incorporating the invention;

Figures 2 and 3 show details thereof;

Figure 4 shows a modified catch bar;

Figure 5 is a cross-section showing a construction alternative to that shown in Fig. 1;

Figure 6 is a plan of the catch bar and certain of the mechanism shown in Fig. 5;

Figure 7 is a front elevation of a part of said catch bar, while

Figure 8 is a section through said catch bar illustrating a stage in its operation.

In these drawings, only those parts of the straight bar knitting machine are shown that are essential to an appreciation of the invention, the remainder of the machine being well understood in the art and needing no illustration or description herein.

Referring primarily to Figs. 1-3, in one construction according to this invention as applied to a Cotton's patent machine the two parts 10a, 10b of the catch bar 10 are guided on suitable guides 11 for separate and conjoint movement in a substantially horizontal direction towards and away from the sinker head 12. The front part 10a is provided with a bar 10c (the falling bar) which is located in front of the sinker butts 13a, 13b and is the equivalent of the front edge or lip of a normal catch bar. The rear part 10b comprises a bar which is adapted to be located behind the sinker butts, and therefore is the equivalent of the rear edge or lip of a normal catch bar. These two parts 10a, 10b may be caused to approach one another so as accurately to locate sinker butts

between them and they are also movable separately towards and away from the head 12. These movements are conveniently derived from separate cams 14, 15 on the main cam shaft 16 of the machine through suitable levers 17, 18 and links 19. The mechanism for moving the parts of the catch bar is so constructed and arranged that, prior to the traverse of the slurcock 20, the front part 10a of the catch bar is moved by cam 15 and truck lever 18 towards the sinker head 12 so that the bar 10c forms a verge plate against which the butts 13a of the jack sinkers 13' may be moved by the slurcock. After the traverse of the slurcock 20 the rear part 10b is likewise moved forward by cam 14, truck lever 17, and links 19, and so pushes the butts 13b of the dividing sinkers 13'' forward and serves to locate the butts of all the sinkers against the bar 10c of the first part 10a. Subsequently the two parts 10a, 10b are retracted in unison so that all the sinkers are retracted as by the normal catch bar.

Means may be provided for adjusting the forward position of the front part 10a of the bar 10, so that after the slurcock 20 has been set a corresponding adjustment may be made to said front part. The front part may be resiliently positioned in its forward position, for example by resilient stops. The said adjustment for the forward position of the front part 10a of the bar 10 may necessitate the provision of means for effecting a corresponding adjustment in the forward position of the rear part 10b of the bar. Thus in Fig. 2 there are shown screw stops 21a, 21b for the respective parts 10a, 10b.

The rear part 10b of the catch bar 10 may have a front lip 10d engaging in front of the dividing sinker butts 13b so that the dividing sinkers 13'' are at all times under complete control, the said lip 10d being arranged to clear the jack sinker butts 13a as will be appreciated from Fig. 1, and the dividing sinker butts 13b being always located between the lip 10d and that face 10e of the rear part 10b that serves to urge the sinker butts forward. The two parts 10a, 10b may be slidably connected, as by screws 23 extending, through slots 22 in part 10a, into part 10b.

In the modified construction of catch bar shown in Fig. 4, a normal falling bar 24 is employed, attached to the sinker head 12.

In a modified construction illustrated in Figs. 5-8 both parts of the catch bar derive their movements towards and away from the sinker head 12 from one and the same source, but since relative movement between the two parts is necessary the front part is frictionally connected to the rear part. For example, the rear part 10b of the catch bar may have any suitable number of rearwardly-extending horizontal friction-box arms 25 on each of which a friction box 26 is secured. The front part 10a of the catch bar likewise has an equivalent number of rearwardly-extending slide rods 27 each of which extends through a friction box 26 aforesaid. Each arm 25 is connected to a rocking lever 28 whereby the rear part 10b of the catch bar is reciprocated, towards and away from the sinkerhead 12, from a cam or cams 29 on the camshaft 16 so that the two parts 10a, 10b will tend to move together but stops 30 (Fig. 6), preferably adjustable, are provided for terminating the retraction of the front part 10a of the catch bar before the termination of the retraction of the rear part 10b thereof, the friction boxes 26 thereafter slipping while the rear part 10b recedes from the front part 10a. It may here be mentioned

that in order to prevent the dividing sinkers 13'' being retracted while the rear part 10b of the catch bar recedes from the front part 10a, the said rear part 10b is not, in this construction, provided with a front lip. When the rear part 10b has reached the extremity of its retirement the two parts of the catch bar are widely separated (Fig. 8) with the butts of the sinkers between them. The rear part 10b is then moved forward, carrying the front part 10a with it until the latter is positioned against the sinker head 12 by other adjustable front stops 31. This permits the jack sinkers to be projected up to the said front part by a slurcock as illustrated in Fig. 1. Thereafter the rear part 10b of the catch bar continues to move forward to advance the dividing sinkers, during which continued forward movement the slide rods 27 slip through the friction boxes 26. At the appropriate stage in the operation of the machine the rear part 10b is retracted, carrying the front part 10a with it, so that all the sinkers are retracted in unison until the motion of the front part of the bar is terminated by the stops 30 first mentioned, after which the friction boxes slip while the rear part of the bar continues to recede for a short distance.

While it is possible so to arrange the friction boxes that their friction is sufficient to cause the front part 10a of the catch bar to travel with the rear part 10b thereof during the retraction of the sinkers it is preferable positively to connect two parts of the bar, for retraction, by means of a releasable connection and to provide means for releasing this connection at or about the time the rearward movement of the front part 10a is terminated by stops 30. To this end at least one (or each) of the slide rods 27 of the front part 10a of the catch bar is formed with a longitudinal slot or groove 32 (Fig. 6) and a pivoted catch 33 is provided on the adjacent operating friction box arm 25 to engage the rear edge of this slot. This catch 33 therefore establishes a mechanical connection between the two bars 10a, 10b so that they are retracted in unison. At or about the time that the retraction of the front part 10a of the bar is to be terminated by its stops 30 the catch 33 travels into contact with a release stop (which may be constituted by any convenient rod or shaft 34 of the machine) which moves it against a spring 35 to disengage from the slot 32 so that the rear part 10b of the catch bar may continue to move rearwardly while the slide rods 27 slip through the friction boxes 26 and the front part 10a remains stationary. As a result, the catch 33 is inoperative to connect the two parts of the catch bar during their forward advance, but drops into the slot 32 when the forward movement of the front part 10a is terminated by the front stops 31.

We claim:

1. In a straight bar knitting machine, having a sinker head for receiving individually-movable and dividing sinkers: a compound catch bar mounted for rectilinear reciprocation toward and from said head, said bar comprising separately movable front and rear members slidably connected for relative movement between them, the former of which members is engageable with all the sinkers to align them in their advanced position and to retract them in unison, and the latter of which members is adapted to advance the dividing sinkers in unison; means for reciprocating both of said members; and means for causing the rear member to reach its forward limit of travel

after the front member has reached its forward limit.

2. In a straight bar knitting machine of the type having a falling bar, sinkers having butts advanced serially up to said bar, and interspersed sinkers having butts advanced in unison up to it, all of said sinkers being retracted in unison: the combination of a catch bar comprising separately movable front and rear parts slidably connected for relative movement between them, said front part being engageable with the front of the butts of all sinkers to retract them in unison, and said rear part being engageable with the rear of the butts of said interspersed sinkers to advance them in unison to the falling bar; means for guiding said catch bar parts for uniplanar rectilinear movements; and operating means for effecting forward movement of said front part prior to the serial advance of the first mentioned sinkers, forward movement of said rear part subsequent to said serial advance to move the interspersed sinkers in unison up to the falling bar, and retraction of the front part to retract all sinkers in unison.

3. A knitting machine according to claim 2, 25 wherein the operating means directly actuates one of said catch bar parts, there being lost motion connections between the bar parts for transmitting motion from one to the other, and also providing for motion of one while the other remains stationary.

4. In a Cotton's patent or other straight bar knitting machine having a sinker bed for sinkers equipped with butts; a catch bar comprising two

separately movable parts, a front part for engaging in front of sinker butts to retract them and a rear part for engaging behind sinker butts to advance them, means for moving said parts towards and away from the sinker bed, and frictional connections between said bar parts whereby one may move while the other remains stationary.

5. In a straight bar knitting machine of the type 10 having a sinker bed for sinkers equipped with butts; a catch bar comprising front and rear parts, mounted for uniplanar movement towards and away from the sinker head, for engaging the butts between them, means for moving the rear part towards and away from the bed, friction box 15 means for coupling the front part to said moving means, a stop for limiting the advance of the front part towards the bed, and a stop for terminating the retraction of the front part from the bed before the rear part reaches the rearward extremity of its travel.

6. In the combination claimed in claim 5, positive means for connecting the front part of the catch bar to the moving means during the retraction of said part, and means for releasing said connection preparatory to the advance of the rear part.

7. The combination stated in claim 2, wherein 30 the rear part of the catch bar has constant engagement with the dividing sinkers to afford complete control of the latter at all times.

THOMAS CHARLES BROMLEY.
ARTHUR SHORTLAND.
